AUTOMATIC RELEASE COLLAR CLAMP

Edmund N. Neckel, Cincinnati, Ohio, assignor to
The American Laundry Machinery Company,
Cincinnati, Ohio, a corporation of Ohio

Application July 3, 1947, Serial No. 758,863

3 Claims. (Cl. 38—13)

1

This invention relates to collar clamps for shirt presses, and more particularly to a clamp which is automatically released for movement to its inoperative or idle position.

One object of the invention is to provide an improved collar clamp which is of unit form in the sense that it may be made and assembled as a distinct unit and in that form may be applied to any shirt press where the bed rises during the final pressing operation, with the assurance that the clamp will be released and move to idle position before full final pressure is applied, all without any especial attention or central operation by the operator.

Another object is to provide an improved collar clamp which is released solely by the effect upon it of the rising collar supporting form to which the collar is secured by the clamp, thus dispensing entirely with any special motor or other operating mechanism for the purpose.

Still another object is to provide improved collar clamping mechanism which is highly efficient in its production of the necessary motions of the clamp, first downward into general cooperative relation with the collar form and then horizontally toward it for clamping purposes, and which also is readily adjustable, over a reasonable range, to vary the degree of horizontal travel and the consequent ultimate clamping effect.

A further object is to provide improved collar clamping mechanism in which the clamp is moved into clamping engagement with the collar form to clamp the collar thereon, by over-center toggle mechanism, said toggle mechanism being of such form and being so arranged that it is capable of being manually advanced to over-center clamping position and is also retracted, across center, to clamp release position by force or motion imparted or applied directly to the clamp itself, rather than to operating mechanism or other parts connected to the toggle mechanism, thus simplifying the device and dispensing with many parts otherwise necessary.

Another object is to provide improved collar clamp mechanism which is of relatively simple form, which is capable of convenient adjustment, which is manually applied and automatically released, which may be made and applied in unit form without necessity of providing a separate operating motor or mechanical operating connections to other press parts, which is reliable and efficient in operation, and which is sturdy and not liable to get out of order in service.

Further objects of the invention in part are obvious and in part will appear more in detail hereinafter.

In the drawings,

Fig. 1 is a side elevation, showing the collar clamping mechanism applied to a shirt press, with the clamp in open or release position;

2

Fig. 2 is a plan view;

Fig. 3 is an end elevation of the clamping mechanism, the view being taken on the line 3—3, Fig. 1;

Fig. 4 is a sectional elevation, on the line 4—4, Fig. 2, showing the clamp in intermediate position;

Fig. 5 is a similar view, on a larger scale, showing the clamp fully applied; and

Fig. 6 is a detail view illustrating the paths of travel involved in clamp operation, and also showing the press bed raised to full pressure relation with the head.

The invention may be used with or embodied in any shirt ironing or pressing machine in which the final pressure effect is produced by upward motion of the bed toward the head. Good examples of such presses are those shown in Patents Nos. 2,082,913, granted June 8, 1937, to John P. Singiser, for Operating and control mechanism for pressing machines, and 1,129,161, granted February 23, 1915, to Gottlob Binder, for Ironing machine.

For convenience, and in no sense of limitation, the drawings show a pressing machine comprising a stationary frame 10 on which is pivotally mounted upon a horizontal axis a lever 11 supporting a hollow, heated head 12 provided with a recess 13 at one end shaped to fit around the shirt neck band or collar and the block upon which it is shaped.

The neckband former or block is indicated at 14. It is mounted upon a padded bed or buck 15 carried by a post 15a vertically slidable in the frame 10. The shirt to be ironed, shown in dot-dash lines at 16, Fig. 1, is dressed upon the padded bed with its neckband or collar surrounding the block or former 14. Then the head is swung down to a position in close neighboring relation with the bed, where it is held solidly against upward thrust, whereupon the bed is caused to rise, carrying the shirt into contact with the head (if it is not already there), and applying full ironing pressure, after which the press is opened in the usual manner.

The head and bed may be operated in any suitable manner, either manually or by power mechanism such as shown in said patents, the specific form of which is of no importance and forms no part of the present invention, which relates entirely to the collar or work clamp and its manner of operation now to be described.

The collar clamp and its operating and control mechanism are so designed that they may be made up and assembled on the bench in unit form ready for application either to a new press or to an old one already in use. All parts are mounted upon a base in the form of a bracket 17 having a split collar 18 by means of which it may be secured to an arm 19 attached to a part of the

press frame 10. By adjustment of the bracket around and along the arm the clamp readily may be mounted in appropriate working relation with the neckband former and press bed with which it cooperates.

Bracket 17 extends upwardly from the arm 19, its upper end being bifurcated to provide two parallel arms 20, 21, in alined bosses of which is journaled a cross shaft 22 on which is fixedly mounted a bell crank member 23. This is provided with depending side arms 24, which are pivotally mounted at 24a the side arms 25 of a yoke 26, to the cross bar of which is adjustably connected, as by a threaded joint at 27, a bent rod 28 supporting the curved plate metal collar clamp and shield 29. A lock nut 30 holds the rod firmly in any position to which it may be adjusted.

One side arm 25 (at the right in Fig. 3) is extended at 31, the extension being provided with a stop ear 32 which in release position of the clamp (Fig. 1) engages a rubber or other yielding bumper 33 on the bracket, thus limiting release motion of the clamp, and which in operating position (Fig. 5) lies opposite the end of an adjustable release abutment or trigger device in the form of a screw 34, later referred to.

Bell crank member 23 is also provided with two arms 35 to which is pivotally connected at 35a (Fig. 3) one end of an eye bolt or rod 36, the opposite end of which passes through a sleeve block 37 having a pin 37a pivotally mounted in a rocker arm 38 fastened to a shaft 39 journaled in the side arms 21 of bracket 17, said shaft being provided on its outer end with a hand crank 40 by means of which the operator manipulates the mechanism. Another part of rocker 38 is bent laterally to form an ear 41 in which is adjustably mounted an abutment screw 42 designed to form a stop, limiting motion of the eye bolt 36 beyond dead center, as will later appear.

Eye bolt 36, on one side of block 37, is provided with a compression spring 43, the tension of which may be adjusted by nuts 44, and on the other side of the block with two lock nuts 45. Adjustment of the several nuts permits the effective length of rod 36 to be increased or diminished. Since this rod 36 cooperates with rocker arm 38 as a toggle, the two members of which are pivotally connected at the knuckle pin 37a, the adjustment enables the amount of horizontal travel of the clamp, after it contacts the bed, to be lengthened or shortened, thus to set it nicely and maintain it in correct relation to the collar block and chest, and with the desired clamping effect, in the press to which the mechanism is applied.

A link 46 pivotally connects the ear 41 to an arm 47 pivotally mounted in the side arm 20, said arm 47 having a lug 48 in which the abutment release screw 34, before mentioned, is adjustable.

Going back to the bell crank member 23, this is provided with upper and lower ears 49, 50, the upper of which forms a perch for a compression spring 51, the lower end of which rests on an ear 52 carried by one of the side arms of yoke 26.

A clamp retracting tension spring 53 connects pins 54, 55, one on the bell crank member and the other serving as the shaft on or with which arm 47 turns.

The operation is as follows:

With the press open, as in Fig. 1, the operator first applies a shirt to the bed, as shown in dot and dash lines at 16. With a detachable collar shirt, the neckband surrounds the block or form-

er, and the collar of an attached turn down collar shirt stands up above the block, as shown.

The parts of the collar clamp are in the positions shown in Fig. 1. The clamp is in fully retracted or release position, with its ear 32 held against the bumper 33 by the biasing tension of spring 53. Ears 52, 50 are held in contact by the compression spring 51. The toggle is broken, with the knuckle pin 37a considerably to the right of dead center. Handle 40 lies in position A.

Now, the operator applies the clamp by grasping the handle 40 and turning it clockwise to position B, moving the parts first to the position shown in Fig. 4. Toggle arm 38 pulls down on toggle rod 36, which turns bell crank member 23 clockwise and brings the clamp down to a position upon and contacting with the shirt, just in front of the collar. Since the clamp rod 28 turns with member 23 about the center of shaft 22, and said shaft lies at about the level of the collar wings, the edge of the clamp follows the dotted path D, Fig. 1, first moving downward and to the right, and then downward and to the left, coming to rest a short distance from the collar.

Advance motion of handle 40 is continued to position C, Fig. 5. The effect is to turn bell crank member 23 still more, but since clamp 29 cannot move down it now slides along the bed to the left into clamping engagement with the collar and form until the motion is terminated by engagement of rod 36 with the end of stop screw 42, which has been brought into active position by the turning of rocker arm 38. The knuckle of the toggle, pin 37a, has also moved beyond dead center, to wit, to a position beyond a line joining the centers at 39, 35a, but it can go no further. Spring supporting lug 52 has moved away from lug 50 and spring 51 is further compressed. Trigger screw 34 is in cocked position and its end lies opposite and close to the ear 32 on the extended arm of the clamp supporting yoke. Spring 43 has been compressed on account of the over travel of crank 38 after motion of bell crank 23 is stopped by engagement of the clamp with the collar block and compression of spring 51. All parts come to rest with the collar or neckband firmly clamped against the collar block.

The operator now proceeds with dressing or arranging the lay of the shirt upon the board, pulling down the shirt front and arranging those parts adjacent the block, as is usual.

Next the press is closed for the ironing operation. As before stated, this is a two-step proceeding. The head is first swung down or lowered from its open position, Fig. 1, to its closed position, Fig. 5, where it is slightly above the bed or at least is in a position short of full pressure engagement therewith. Here the head stops and is held rigidly, in the usual manner. The bed now rises to apply the work to the head with full ironing pressure. It is this upward bed motion which releases the work clamp.

As the bed rises, it carries the clamp with it, as indicated by the dot-dash lines P, Fig. 5. This turns the clamp yoke 26 counterclockwise about the pivot 24a, and the yoke extension lug or ear 32 becomes effective upon the cocked trigger screw 34 and moves the same and stop lever 41 on which it is mounted clockwise. Link 46 transmits this motion to rocker arm 38 and swings the lower end of eye bolt 36 back over center, thus unlocking or breaking the toggle mechanism. Spring 53 now becomes effective to retract the clamp to full release or open position.

It will be observed that when the clamping

member is rising with the bed it rotates about pivotal axis 24a. This, plus the inertia of the clamp rod and shield plate, and their upwardly inclined position, causes the clamp to begin its return motion along a modified path, as shown in Fig. 6. Here, E is the path of travel about pivot 24a and D the path about pivot 22. F is the composite return path due to the influences referred to, which allows the clamp to first clear the head or chest 12 and move away from the collar block, and then revert to and return along the original path D as it completes its return to open position.

Lengthening of the clamp rod 28, by adjustment at the threaded joint 27 causes the clamp to contact the bed further away from the collar block. The nuts 44, 45 on the eye bolt are then adjusted higher on the bolt. This permits the rocker arm 38 to travel farther before the toggle knuckle goes over dead center and consequently increases the travel of the bell crank 23 after the clamp engages the bed or buck, resulting in a corresponding increase in horizontal travel of the clamp. Thus, the adjustments described permit very close setting of the parts in correct relation to the collar block and chest of any press to which they may be applied.

It will also be observed, from the relative positions of the manual or handle 40 in Figs. 1, 4 and 5, that the clamp is very quick acting and unusually powerful in its clamping effect. Very little travel of the manual, from A to B, brings the clamp down upon the bed, while its remaining travel of slightly more than a quarter turn or 90° is utilized to produce horizontal clamp motion and the clamping effect.

Other advantages of the invention will be apparent to those skilled in the art.

What I claim is:

1. A shirt pressing machine of the character described, comprising a stationary frame, cooperating relatively movable head and bed members movably mounted thereon, the head being movable downwardly from open to safe closed position to close the press and the bed being movable upwardly against the closed head to apply final heavy pressure to the work, a neck band supporting block mounted upon the bed, and means for clamping the neck band thereto, comprising an arm pivotally mounted upon the frame and carrying a clamp adapted for embracing and clamping relation with a neck band on said block, means normally biasing said arm toward clamp release position, and manually operated mechanism for turning said arm in one direction to advance the clamp to clamping relation with the block, said mechanism including releasable means effective upon the arm for holding the clamp in clamping position, and means operated by rising bed motion and thereby effective by way of the clamp upon the arm to release the releasable means and permit automatic retraction of said arm to clamp open position.

2. A shirt pressing machine of the character described, comprising a stationary frame, cooperating relatively movable head and bed members movably mounted thereon, the head being movable downwardly from open to safe closed position to close the press and the bed being movable upwardly against the closed head to apply final heavy pressure to the work, a neck band sup-

porting block mounted upon the bed, and releasable means for clamping the neck band thereto, comprising an arm pivotally mounted upon the frame and carrying a clamp adapted for embracing and clamping relation with a neck band on said block, means normally biasing said arm toward clamp open position, and manually operated mechanism for turning said arm in one direction to advance the clamp to clamping relation with the block, said mechanism including releasable over center toggle mechanism having a knuckle movable across dead center to a holding position as the clamp is advanced to clamping position, said toggle mechanism being so arranged that as the bed rises to apply final pressure to the work consequent rising motion of the clamp with the bed retracts said arm and returns the toggle knuckle across dead center to a position in which the arm is subjected to its bias means and is thereby returned to clamp open position.

3. A shirt pressing machine of the character described, comprising a stationary frame, cooperating relatively movable head and bed members movably mounted thereon, the head being movable downwardly from open to safe closed position to close the press and the bed being movable upwardly against the closed head to apply final heavy pressure to the work, a neck band supporting block mounted upon the bed, and releasable means for clamping the neck band thereto, comprising an arm pivotally mounted upon the frame and carrying a clamp adapted for clamping engagement with a neck band on said block, a manually operable rocker member also pivoted in said frame, a rod pivotally connected to said rocker member and cooperating as a toggle therewith, a trigger device operatively connected to one of the toggle members, means biasing the toggle members in either direction from dead center, said rod being operatively connected to said arm in such manner that turning motion of said rocker member in one direction advances the toggle across dead center and the trigger device to cocked position and the clamp to a toggle maintained clamping position, and said arm having a portion which moves to a position opposite the trigger device when the clamp is advanced to clamping position, in such manner that initial retracting motion of said arm consequent upon rise of the clamp with the bed as the latter rises to apply final pressure actuates the trigger device and moves the toggle members reversely across dead center to release the clamp for motion to full open position.
